United States Patent Office.

JOHN BARCLAY, OF ATTLEBOROUGH, MASSACHUSETTS.

Letters Patent No. 94,064, dated August 24, 1869.

IMPROVEMENT IN THE MANUFACTURE OF PLATED-METAL BRACELETS.

The Schedule referred to in these Letters Patent and making part of the same.

To all persons to whom these presents may come:

Be it known that I, JOHN BARCLAY, of Attleborough, in the county of Bristol, of the State of Massachusetts, have invented a new and useful Invention having Reference to Hollow Bracelets; and do hereby declare the same to be fully described in the following specification, and represented in the accompanying drawings, of which—

Figure 1 is a top view,

Figure 2, a side elevation, and

Figure 3, a transverse section of a plated-metal bracelet, made in accordance with my invention.

Figure 4 is a similar section on an enlarged scale.

Figure 5 is a section, on an enlarged scale, of a plated-metal hollow bracelet, as heretofore commonly made.

The bracelet, as ordinarily made of plated metal, that is, a metal plated with gold or other metal, is formed of two pieces, A B, (see fig. 5,) soldered together at their junctions, *a a*.

In the said figure, *b b* denote the plating-metal, and *c c* the foundation-metal or plates on which the plating-metal is fixed.

The upper portion, A, before being applied and fixed to the lower portion B, is bent in the form shown in section in the said fig. 5.

The soldering of the two having taken place, the edges of the plate B have to be filed down even with the outer sides of the part A. This leaves the edges of the baser metal plate *c* exposed, without any covering or plating of gold.

In a bracelet made on my improved plan, these edges are not exposed, but are entirely covered.

In the production of my invention, I bend or turn up the lower plate, shown at C, in fig. 4, at each of

its opposite edges, in manner as represented in such figure, each edge of the plate, after such bending, may have been effected, resting upon or being directly over the upper or unplated surface of the plate, the whole being so as to form beads, E E, on the flanks of the plate, and with the plating *p p* on the external surface of the plate and such beads.

The fellow-piece D, bent as shown in section in fig. 4, and having the plating *p p* on its outer surface, is next to be placed on the piece C, and between the beads E E, and soldered to the said piece C.

The edges of the plating of both plates, C D, will rest directly on, or be immediately over the plate C, and the edges of the baser metal will be completely covered and unexposed.

The bracelet, when so made, will have the appearance as exhibited in figs. 1, 2, and 3.

The beads E E will render the inner plate C, employed in making the bracelet, much stiffer and stronger than it would be without them, and, in fact, will cause the bracelet not only to be stronger, but to present a more ornamental appearance.

They will also completely hide the solder from view, and cause it to take to better advantage than it otherwise would, or, in other words, they will cause it to effect a much firmer union of the two plates.

I therefore claim the improved manufacture of plated-metal bracelet, as made with the turned parts or beads E E, arranged, with respect to the plates C D and their platings *p p*, in manner substantially as represented and described.

JOHN BARCLAY.
